[57] CLAIM

The ornamental design for sleeping bag for children or the like, substantially as shown and described.

DESCRIPTION

FIG. 1 is a top plan view of a sleeping bag for children or the like showing our new design;
FIG. 2 is a side elevational view thereof; and
FIG. 3 is a perspective view thereof in an open position.
The bottom is plain and unornamented.
